Patented Feb. 22, 1921.

Inventor

R. E. Perkins

By *Watson E. Coleman*
Attorney

UNITED STATES PATENT OFFICE.

RICHARD E. PERKINS, OF JOPLIN, MISSOURI.

FOUNTAIN-PEN.

1,369,185.

Specification of Letters Patent. Patented Feb. 22, 1921.

Application filed February 21, 1920. Serial No. 360,297.

To all whom it may concern:

Be it known that I, RICHARD E. PERKINS, a citizen of the United States, residing at Joplin, in the county of Jasper and State of Missouri, have invented certain new and useful Improvements in Fountain-Pens, of which the following is a specification, reference being had to the accompanying drawings.

10. This invention relates to certain improvements in fountain pens, and it is an object of the invention to provide a device of this general character with novel and improved means whereby the nib or pen point may be moved or adjusted longitudinally of the feed bar to regulate or control the flow of the ink.

Another object of the invention is to provide a novel and improved fountain pen 20 wherein the writing end portion of the barrel has engaged therewith a rotatable member operatively engaged with the nib or pen point whereby the pen point or nib may be moved longitudinally with respect to the feed bar and independently thereof so that the flow of ink may be stopped or the pen point or nib be so positioned to get a heavy flow of ink or a light flow of ink or any intermediate degree of flow to suit the individual user or the character of writing desired.

The invention consists in the details of construction and in the combination and arrangement of the several parts of my improved fountain pen whereby certain important advantages are attained and the device rendered simpler, less expensive and otherwise more convenient and advantageous for use, as will be hereinafter more 35 fully set forth.

The novel features of my invention will hereinafter be definitely claimed.

In order that my invention may be the better understood, I will now proceed to describe the same with reference to the accompanying drawings, wherein:

Figure 1 is a view partly in longitudinal section and partly in elevation, illustrating a fountain pen constructed in accordance 50 with an embodiment of my invention;

Fig. 2 is an enlarged fragmentary view in section of the writing end portion of a fountain pen illustrating my improvements in detail; and

Fig. 3 is a fragmentary view in top plan 55 of the pen point or nib as herein embodied.

As disclosed in the accompanying drawings, B denotes a barrel, preferably constructed in accordance with the embodiment of my invention as particularly disclosed in 60 my co-pending application, Serial No. 352,381, and which has extending in the writing end portion thereof a feed bar F. The feed bar F is of substantially the same construction as embodied in my co-pending 65 application, Serial No. 352,382, and which feed bar F is provided in its forward end portion with a pocket or recess 7 serving as a trap to retard the flow of the writing fluid and also serving as a reservoir to hold a surplus of writing fluid in order that the delivery of the fluid through the nib or pen point N can be materially facilitated. The recess or pocket 7 is also in suitable communication with the conduit 1 extending 70 longitudinally of the feed bar F and through which the writing fluid within the barrel B or more particularly the tubular member or reservoir 5 flows to the pocket or recess 7. The major portion of the feed bar 80 F from its writing end to a point in close proximity to its opposite end is of reduced thickness and whereby is provided the shoulder or stop 2. The portion of the feed bar F in advance or forwardly of the stop 85 90 constitutes the working face of the feed bar and said working face is substantially convex in cross section. The nib or point N is substantially concavo-convex 95 in cross section with the radius of the concave face thereof substantially the same as the radius of the convex working face of the feed bar F so that when the nib or point N is in applied or working position, the concave face of the feed bar F will have substantially close contact with the working or concave face of the nib or point N with the inner end portion of the split or opening a in the writing end of the nib or point N 100 overlying the pocket or recess 7.

When the pen is not in use, the applied nib or point N is adapted to close the pocket or recess 7 and which is accomplished by moving the nib or point N longitudinally of the feed bar to position the inner end 105 of the split or opening a either in advance of or rearwardly of the pocket or recess 7. During a writing operation, however, the

opening *a* or the inner end of the split of the nib or point *N* is adapted to overlie or partially overlie the pocket or recess 7 whereby the requisite flow of the writing fluid to the writing end of the nib or point *N* is permitted as the resultant flexure of said end portion of the nib or pen causes the same to move away or separate from the working face of the feed bar. The quantity 10 or amount of such flow is dependent upon the extent to which the inner end portion of the split or opening *a* of the nib or point *N* overlies the pocket or recess 7. The more the inner end portion of the split or opening 15 *a* overlies the pocket 7, the greater the flow of the writing fluid and vice versa.

Threaded upon the writing end portion of the barrel *B* is a sleeve or cap 3 which, upon requisite rotation, moves either outwardly or inwardly with respect to the barrel *B*. The outer end portion of the sleeve or cap 3 is provided with the head 4, having the central opening 6 and which opening is defined by the outstanding nipple or sleeve 8. The writing end portion of the feed bar 25 *F* and the nib or point *N* is disposed through the sleeve or nipple 8 and the opening 6 with the nib or point *N* snugly engaged between the working face of the bar *F* and the adjacent inner wall of the nipple or sleeve 8.

The nipple or sleeve 8, at a predetermined point intermediate its ends, is provided with the interior annular groove or channel 9 in which snugly engages a transversely disposed outstanding bead 10 carried by the nib or point *N* and which bead or rib is preferably pressed out from said point or nib. As the sleeve or cap 3 is rotated, the nib or point *N* will be moved inwardly or outwardly with respect to the feed bar *F* in accordance with the direction of rotation of the sleeve or cap 3 so that effective means are provided whereby the nib or point *N* may be moved or adjusted to regulate or 40 control the flow of the writing fluid. The inner end of the nib or point *N* contacts with the shoulder 2 of the feed bar *F* to limit the inward movement of the nib or point *N* with respect to said feed bar *F* and when at 45 the limit of such movement, the inner end of the split or opening *a* is positioned inwardly of the pocket or recess 7 with the split of the point or nib *N* extending across the pocket or recess 7 so that the flow of the 50 writing fluid is slight. This same result will occur in the event the nib or point *N* is moved outwardly to position the inner end of the split or opening *a* entirely in advance of said recess or pocket 7.

60 I also find it of advantage to provide the inner wall of the barrel *B* adjacent its writing end with the interior recess or groove 12 extending longitudinally thereof and in which is positioned a spring 14, preferably 65 of a bow type and which engages the adja-

cent portion of the nib or point *N* to maintain said point or nib *N* pressed close to the adjacent or working face of the feed bar *F* to prevent leakage of the writing fluid between the inner face of the nib or point *N* 70 and the adjacent working face of the feed bar *F*.

From the foregoing description, it is thought to be obvious that a fountain pen constructed in accordance with my invention 75 is particularly well adapted for use by reason of the convenience and facility with which it may be assembled and operated, and it will also be obvious that my invention is susceptible of some change and modification without departing from the principles and spirit thereof, and for this reason I do not wish to be understood as limiting myself to the precise arrangement and formation of the several parts herein shown 80 in carrying out my invention in practice except as hereinafter claimed.

I claim:

1. A fountain pen comprising, in combination, a barrel, a feed bar extending within said barrel, a face of the feed bar being provided with a pocket, said feed bar being provided with a delivering conduit leading to the pocket, a nib normally in contact with the working face of the feed bar and extending within the barrel, and means for adjusting the nib independently of the feed bar to control the inner end portion of the split of the nib with respect to the pocket. 95

2. A fountain pen comprising, in combination, a barrel, a feed bar extending within said barrel, a face of the feed bar being provided with a pocket, said feed bar being provided with a delivering conduit leading to the pocket, a nib normally in contact with the working face of the feed bar and extending within the barrel, and means for adjusting the nib independently of the feed bar to control the inner end portion of the split of the nib with respect to the pocket, 100 105 said means being carried by the barrel.

3. A fountain pen comprising, in combination, a barrel, a feed bar extending within said barrel, a face of the feed bar being provided with a pocket, said feed bar being provided with a delivering conduit leading to the pocket, a nib normally in contact with the working face of the feed bar and extending within the barrel, means for adjusting the nib independently of the feed bar to control the inner end portion of the split of the nib with respect to the pocket, 110 115 and means for constantly urging the inserted end portion of the nib toward the feed bar.

4. A fountain pen comprising, in combination, a barrel, a feed bar extending within said barrel, a face of the feed bar being provided with a pocket, said feed bar being provided with a delivering conduit leading 120 125 130

to the pocket, a nib normally in contact with the working face of the feed bar and extending within the barrel, and a member carried by the barrel and adjustable longitudinally thereof, said member and nib being provided with coacting means whereby the nib is caused to move in unison with the member in a direction longitudinally of the barrel.

5 10 5. A fountain pen comprising, in combination, a barrel, a feed bar extending within said barrel, a face of the feed bar being provided with a pocket, said feed bar being provided with a delivering conduit leading to the pocket, a nib normally in contact with the working face of the feed bar and extending within the barrel, and a member carried by the barrel and adjustable longitudinally thereof, said member including a

15 20 sleeve surrounding a portion of the feed bar and the nib, said sleeve and nib being provided with a coacting rib and annular

groove whereby movement of the member longitudinally of the barrel imparts corresponding movement to the nib independently of the feed bar. 25

6. A fountain pen comprising, in combination, a barrel, a feed bar extending within said barrel, a face of the feed bar being provided with a pocket, said feed bar being provided with a delivering conduit leading to the pocket, a nib normally in contact with the working face of the feed bar and extending within the barrel, and a member in threaded engagement with the barrel and adjustable longitudinally thereof, said member and nib being provided with coacting means whereby the nib is caused to move in unison with the member in a direction longitudinally of the barrel. 30 35 40

In testimony whereof I hereunto affix my signature.

RICHARD E. PERKINS.
